US0D1049688S

(12) **United States Design Patent** (10) **Patent No.:** **US D1,049,688 S**
(45) **Date of Patent:** **** Nov. 5, 2024**

(54) **DISPLAY STAND**

(71) Applicant: **Tern (Xiamen) Technology Co., Ltd.**,
Fujian (CN)

(72) Inventor: **Lianming Su**, Fujian (CN)

(73) Assignee: **Tern (Xiamen) Technology Co., Ltd.**,
Xiamen (CN)

(**) Term: **15 Years**

(21) Appl. No.: **29/941,769**

(22) Filed: **May 11, 2024**

(51) LOC (14) Cl. **06-04**

(52) U.S. Cl.
USPC **D6/682.2**

(57) **CLAIM**

The ornamental design for a display stand, as shown and described.

DESCRIPTION

FIG. 1 is a first perspective view of a display stand showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines in the drawings depict portions of the display stand that form no part of the claimed design.

1 Claim, 8 Drawing Sheets
